United States Patent Office.

D. L. HOLDEN, OF NEW ORLEANS, LOUISIANA.

Letters Patent No. 66,025, dated June 25, 1867.

PETROLEUM GAS-BURNER FOR HEATING PURPOSES.

The Schedule referred to in these Letters Patent and making part of the same.

TO ALL WHOM IT MAY CONCERN:

Be it known that I, D. L. HOLDEN, of the city of New Orleans, parish of Orleans, and State of Louisiana, have invented a certain new and useful improvement in Petroleum Gas-Burners; and I do hereby declare the following to be a full, clear, and exact description of the same, reference being had to the annexed drawings, making a part of this specification, in which—

Figure 1 is a perspective view of a burner that contains my improvement; and

Figure 2, a sectional view of the same.

My invention consists of a concentric chamber to contain the oil around an interior or central air-chamber or flue, and the effect accomplished by it is a more rapid generation of gas, and a consequent intense heat than obtains in the burners of Gray, Seroni, Dopp, Jersey, and all others with which I have any acquaintance.

Referring to the drawings, A represents a burner, B the central air-chamber, and C the concentric oil-chamber that I have devised.

In the operation of my burner the oil enters the concentric chamber through the pipe D, which, it will be understood, is provided with valves and mechanical appliances to prevent leakage, and completely surrounds the central air-chamber B. Heat being applied in any usual manner, (and, from the construction of my burner, it will be seen that this can be done in so general and diffuse a manner that the heat will be brought to bear upon the oil on all sides,) gas or vapor is quickly generated, and, issuing from the oil within the concentric chamber C, enters the central air-chamber, near the top thereof, through the apertures or vent-holes D'. Issuing as soon as the evolution of gas begins it can be lighted by the application of a flame to the vents D'. Issuing from these vents, the burning gas impinges upon the walls of the air-chamber, and quickly superinduces therein a very great degree of heat. The walls being thus heated, the evolution of gas becomes more rapid, and this induces a more rapid combustion. The result is, to produce and to keep up a very intense degree of heat, which is the object sought after. If a still greater heat be desirable, it can be produced by the application of a short metallic chimney fitted over the burner, and resting upon the flanch E, which, it will be observed, encircles the burner; or, if a distribution of the heat or flame above the burner be required, a perforated metallic cap may be applied with the certainty of attaining a general diffusion of the said flame.

In manufacturing my burner I either cast it as an entirety, or the two chambers B and C may be established by the insertion of the section of a pipe on the plan shown upon the drawings. I do not limit myself to any particular or specified mode of making my invention, that is to say, of manufacturing it.

Having thus described my invention, what I claim, and desire to secure by Letters Patent, is—

A gas retort and burner, consisting of the concentric or annular oil-chamber C, in combination with a central air-chamber or flue, B, provided with perforations D' at or near the top of chamber C, substantially as and for the purpose described.

D. L. HOLDEN.
